Primary Examiner — Garth Rademaker*Assistant Examiner* — Omeed Agilee(74) *Attorney, Agent, or Firm* — Neal, Gerber &
Eisenberg LLP; Thomas E. Williams(57) **CLAIM**

The ornamental design for a bottle, as shown and described.

DESCRIPTIONFIG. 1 is a front, right, and top perspective view of a bottle,
showing our new design;

FIG. 2 is a rear, left, and top perspective view thereof;

FIG. 3 is a front, right, and bottom perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines are included for illustrating portions of the
bottle that form no part of the claimed design.**1 Claim, 7 Drawing Sheets**(56)
